Howes & Sons

UNITED STATES PATENT OFFICE.

HENRY C. LEES, OF PHILADELPHIA, PENNSYLVANIA, ASSIGNOR TO SCHRACK & SHERWOOD, OF SAME PLACE.

DESIGN FOR AN UPHOLSTERY-BAND.

SPECIFICATION forming part of Design No. 15,471, dated October 21, 1884.

Application filed January 3, 1884. Term of patent 7 years.

To all whom it may concern:

Be it known that I, HENRY C. LEES, a citizen of the United States, and a resident of Philadelphia, Pennsylvania, have invented or 5 produced a new and original Design for an Upholstery-Band, of which the following is a specification.

My design for an upholstery-band is shown in the accompanying drawings, in which Figure 1 represents a short strip of the band sufficient to illustrate the design, and Fig. 2 a transverse section of the same.

The band comprises the central row of balls, *a*, and one or more rows of tufts, or, as they 15 are generally termed, "half-cuts," *b*, on each side of the same, two rows on each side being shown in the drawings, although there may be but one row, or more than two rows on each side, without departing from the main 20 feature of the design. Outside of the rows of half-cuts are cords *d*, and beyond the latter looped threads *f*.

Although "balls" is the name given in the trade to the ornaments *a*, they are not actually 25 round, but have flat backs, the fronts of the balls, however, being raised and rounded, or hemispherical; and it is in this respect that

my design is distinct from others of this class in which flat buttons form the central ornaments, as in Dreyfus's Patent No. 12,788, February 21, 1882.

I claim—

1. The design for an upholstery-band, said design consisting of the central row of raised balls, *a*, and one or more rows of tufts or half-cuts, *b*, on each side thereof, all substantially as described and shown.

2. The design for an upholstery-band, said design consisting of the central row of raised balls, *a*, the row or rows of tufts or half-cuts *b* on each side thereof, and the outer cords, *d*, as shown and described.

3. The design for an upholstery-band, said design consisting of the central row of raised balls, *a*, the row or rows of tufts or half-cuts *b* on each side thereof, the cords *d*, and the outer looped threads, *f*, as set forth.

In testimony whereof I have signed my name to this specification in the presence of two subscribing witnesses.

HENRY C. LEES.
